UNITED STATES PATENT OFFICE.

EDWARD E. CLEMENT AND HARRY F. LOWENSTEIN, OF WASHINGTON, DISTRICT OF COLUMBIA, ASSIGNORS TO EDWARD F. COLLADAY, OF WASHINGTON, DISTRICT OF COLUMBIA.

RADIO RECEIVING APPARATUS.

Application filed July 8, 1924. Serial No. 724,886.

Our invention relates to combined broadcasting and telephone systems, and has for its object the provision of improved means by which an operator at a radio switchboard 5 may supervise the operation of a radio receiving apparatus at a subscriber's station, the present invention being in the nature of an improvement over that described and claimed in Letters Patent No. 1,522,308, 10 granted to us January 6, 1925.

In said patented system we provide a test or listening relay at the subscriber's station, connected to the telephone wire circuit and controlled by a radio operator at central to 15 connect the substation radio receiving apparatus or circuits to the wire circuit for telephonic transmission thereover to central, whereby the said radio operator may listen to the actual sounds received and reproduced 20 at the substation while broadcasting, with a view to the regulation and adjustment of the transmitting instrument or the receiving instrument, or both. In the present case, we provide for such supervision by 25 connecting a telephone transmitter to the contacts of the listening relay, and so relating said transmitter to the receiver or loud speaker of the radio receiving set that direct mechanical conduction of sound waves 30 takes place between them, and a test of the complete performance of the apparatus as a whole is possible.

Our invention is illustrated in the accompanying drawings, in which

Fig. 1 is a diagram showing a central office having a telephone switchboard and a radio switchboard, a subscriber's station equipped with a telephone and a radio receiving set, and the line circuit therefrom 40 to central.

Fig. 2 is a modification of the subscriber's loud speaker and audio supervisory means.

Fig. 3 is a side view of the combined loud speaker and telephone transmitter shown 45 diagrammatically in Fig. 1.

Referring to the drawings, C is the central office which for convenience is shown equipped with manual apparatus, but which may have automatic switching apparatus, 50 for the interconnection of telephone lines, or for the radio station control, or both. The line 16-17 is connected as usual to terminals on the telephone switchboard and to one or more multiple terminals on the radio

switchboard, where the radio operator has 55 cord circuits typified at P^x, equipped with a switch K^x for connecting battery to the tip side of line, the cut off relay of the line being at the same time energized to clear said side of ground at the central office, which is 60 normally connected through the windings of the line relay.

At the substation A, the telephone T is a standard common battery instrument set. The radio receiving apparatus is equipped 65 with another telephone set, comprising a transmitter T', receiver t', induction coil I, switch H' and condensers q³, q⁴. The radio set in itself forms no part of the present invention, but to supply a loud speaking horn 70 for our purposes, is shown as having a detector tube 30, and two stages of audio amplification by tubes 31 and 32. The usual transformers 33, 34, 35 are provided, with batteries A' and B' for filaments and plates. 75 The horn 36 and the switch H' are so related that when the telephone T' is turned up to open the switch H' it will be in position to receive sound waves from the horn. When the switch H' is closed it closes the filament 80 circuits as follows: A', 25, 42, H', 41, filaments, battery. When the switch is open, the radio operator at central can close the filament circuit and also the circuit of transmitter T by energizing relay L⁵. For this 85 purpose, key K^x is closed, and battery current flows over tip side 16 of line to the substation, thence through back contact of cut off relay L⁴ by wire 26 to L⁵ and ground.

L⁵ becoming energized, closes the following 90 circuits: filament circuit from A', 25, 27^a, 37, 43; transmitter circuit from A' to 25, 27^b, T', I, and back to battery, shown as by ground return, but may be by wire; line transmission circuit: 16, contact of L⁴, 26, 27^c, 39, q⁴, 95 t', I, q³, 40, 27^d, back contact of L⁴, and so to sleeve side 17 of line. The operator thus controls both the filament circuit and the repeat back circuit, and may receive the actual sound waves produced by the loud 100 speaker, by transmission through the body or frame of the horn thereof and through the arm of the transmitter T' joined to the horn at J²⁰ (see Fig. 3). The arrangement of this transmitter arm it will be noted, is 105 such as to permit the transmitter itself to be used when desired as a "mute" to muffle the sound proceeding from the horn. The me-

- chanical structure of this device is best shown in Fig. 3 where T' indicates the transmitter and J²⁰ represents the hinged joint made with firm connection between its relatively movable part to render it a good conductor of sound vibration. In this form, we provide switch H' in the form of a push button with normal open contact arranged to be closed by the transmitter when pushed down into the dotted line position, in which position it will be noted the transmitter may be employed by the subscriber for ordinary telephonic purposes. The transmitter may also be thus employed without closing the contacts of switch H' by adjusting the arm in an intermediate position.

Fig. 2 shows a modification in which the transmitter T' is permanently secured by rigid mechanical means on the neck of the horn 36, so that sound vibrations may be directly communicated to the transmitter. In this case the switch H' may remain in the form shown in our patent but would have to be worked manually to close the filament circuits.

It is to be understood that the mechanical connection of the transmitter may be varied without departing from the invention, as for example by connecting it on a metal rod or other metal connection to the base or source of vibration of the loud speaker.

We claim:

1. A combined superaudio frequency and telephone transmission system comprising a receiving station, a supervising station therefore, and a telephone line interconnecting the two, a superaudio frequency receiving and detecting apparatus in said receiving station, including a telephone receiver con-

nected to its output circuit, and a telephone transmitter mechanically connected to said receiver for mechanical transmission of sound waves therebetween, and electrically connected to said telephone line, whereby signals received at the receiving station, as modulations on a superaudio frequency carrier may be transmitted at audio or telephone frequency over the telephone line to the supervisory station.

2. In a combined radio and telephone station, a radio receiving set having a receiver connected to its output circuit, a telephone transmitter mechanically connected with the frame or shell of said receiver and movable thereon, and switching contacts also on said receiver controlling the operating circuits of said radio set and themselves controlled in the movement of said transmitter on said receiver.

3. In a combined radio and telephone system comprising a receiving station having a radio receiving set and a supervisory station connected with the receiving station by a telephone line, a receiver connected to the output circuit of said radio set, a telephone transmitter mechanically mounted on the frame or shell of said receiver so as to be movable thereon into and out of operative position, switch contacts also on said receiver controllable in the movement of the transmitter for opening and closing the operating circuits of the radio set, and circuit connections from said transmitter to said telephone line.

In testimony whereof we hereunto affix our signatures.

HARRY F. LOWENSTEIN.
EDWARD E. CLEMENT.
